UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

WIRE-GRIPPING MECHANISM.

1,111,878.

Specification of Letters Patent. Patented Sept. 29, 1914.

Application filed November 28, 1910. Serial No. 594,441.

To all whom it may concern:

Be it known that I, ELBERT H. CARROLL, a citizen of the United States, residing at Worcester, in the county of Worcester and 5 Commonwealth of Massachusetts, have invented a new and useful Improvement in Wire-Gripping Mechanism, of which the following is a specification, accompanied by drawings forming a part of the same.

10 The objects of my invention are to provide a wire gripping mechanism designed to be used in connection with a rotating wire drawing block for holding the end of the wire at the beginning of the drawing operation, having means by which the jaws of 15 the gripping mechanism may be opened by the attendant, and being capable of automatically seizing and holding the wire. These objects, among others, I accomplish 20 by means of the construction and arrangement of parts as hereinafter described and pointed out in the annexed claims.

In the accompanying drawings, Figure 1 represents a side elevation of a wire drawing block provided with a gripping mechanism embodying my invention. Fig. 2 is a detached perspective view of the gripping mechanism with the jaws in a closed position. Fig. 3 is a detached perspective view 25 with the jaws opened, and Fig. 4 is a sectional view on the plane of the broken line 4—4, Fig. 3.

Similar reference characters refer to similar parts in the different figures.

30 Referring to the accompanying drawings, 1 denotes a rotatable wire drawing block to which is connected by a chain 2 a wire gripping mechanism 3 embodying my present improvement. The gripping mechanism 35 comprises a pair of opposing jaws 4 and 5 pivotally connected on opposite sides by links 6, 7, and 8, 9. Extending upwardly from the jaw 4 is an arm 10 and extending 40 upwardly from the jaw 5 is an arm 11, said 45 arms being preferably curved in order that the arm 10 may fit the palm of the hand and the arm 11 be conveniently grasped by the fingers, as shown in Fig. 3, for the purpose of bringing the arms together and rocking 50 the jaw 5 on its pivotal connection with the jaw 4 to separate the jaws for the insertion of the end of the wire between them.

Between the arms 10 and 11 I interpose a 55 spring 12 having its ends bearing against the opposing surfaces of the arms, with its

tension applied to hold the arms normally separated with the jaws 4 and 5 in a closed position, as shown in Fig. 2. The face 13 of the jaw 4 is preferably smooth, while the face 14 of the jaw 5 is preferably toothed or 60 serrated. The toothed face 14 is preferably formed on a detachable bar 15, having a projection 16 interlocking the jaw 5 to prevent the longitudinal movement of the detachable bar 15. The bar 15 is held in 65 place by means of a screw 17.

In order to insert the end of the wire between the jaws 4 and 5 the arms 10 and 11 are compressed by hand, causing the jaw 5 to be rocked on the links 6, 7 and 8, 9 the 70 ends of which links are pivotally connected to said jaws and separated from the jaw 4, as shown in Fig. 3, sufficiently to allow the insertion of the end of the wire 18, Fig. 1. When the arms 10 and 11 are released, the 75 spring will reverse the motion of the jaw 5 and bring the opposing faces of the jaws firmly against the end of the wire. The distance between the pivotal centers of the links 7 and 9 is slightly less than the distance 80 between the pivotal centers of the links 6 and 8, so that when the opposing faces of the jaws are in their closed position, as shown in Fig. 2, the opposing faces will be slightly divergent, or separated at their 85 outer ends while in contact at their inner ends, so that pressure is first applied to the end of the wire 18. When the wire drawing block 1 is started and a strain exerted upon the wire 18, the teeth carried 90 by the jaw 5 will be drawn into the body of the wire at gradually decreasing depths from the inner toward the outer ends of the jaws, thereby preventing the undue weakening of the wire caused by the incision of the 95 teeth and reducing the liability of breaking the wire between the opposing faces of the jaws. The jaw 4 is provided with a hole 19 to receive a hook or link of the chain 2.

I claim,

1. A wire gripping mechanism, comprising a pair of opposing gripping jaws, links pivotally connected to said jaws, and upwardly extending arms on each of said jaws adapted to be compressed by hand for opening the jaws.

2. In a wire gripping mechanism, the combination of a pair of opposing gripping jaws, links pivotally connected to said jaws, upturned arms projecting from each of said 110

jaws, and a spring interposed between said arms to separate them and hold the jaws in a normally closed position.

3. In a wire gripping mechanism, a pair of wire gripping jaws, a pair of links each pivotally connected to said jaws, and means extending from each one of said jaws in coöperating relation to the means extending from the other of said jaws to provide for
10 the opening of said jaws.

4. In a wire gripping mechanism, a pair

of wire gripping jaws, links pivotally connected to each of said jaws, and means adapted to be operated to open said jaws, comprising an arm extending from each of 15 said jaws.

Dated this 23rd day of November 1910.

ELBERT H. CARROLL.
